CLAIM

The ornamental design for a sheet receiver for a patient repositioning system, as shown and described.

DESCRIPTION

FIG. 1 is a front perspective view of a first embodiment of a sheet receiver for a patient repositioning system according to the present invention.

FIG. 2 is a rear perspective view of the sheet receiver shown in FIG. 1.

FIG. 3 is a front view thereof.

FIG. 4 is a right side view thereof; the left side view being a mirror image thereof.

FIG. 5 is a rear view thereof.

FIG. 6 is a top view thereof; and,

FIG. 7 is a bottom view thereof.

The broken lines adjacent to shaded or sectional portions are an unclaimed boundary of the design and form no part of the claimed design.

The dash-dot lines are shown for environmental purpose only and form no part of the claimed design.
